CLAIM

The ornamental design for a spice mill, as shown and described.

DESCRIPTION

1. Spice mill

1.1 is a top plan view of a spice mill showing my new design;

1.2 is a top front perspective view thereof;

1.3 is a front elevational view thereof; and

1.4 is a bottom plan view thereof.

The broken lines in FIG. 1.4 are included for the purpose of illustrating environment and form no part of the claimed design.
